CLAIM

The ornamental design for a computer, as shown and described.

DESCRIPTION

FIG. 1 is a top perspective view of a computer according to the design, showing the display in a landscape orientation. FIG. 2 is a bottom rear perspective view of the computer shown in FIG. 1.

FIG. 3 is a left-side view of the computer shown in FIG. 1. FIG. 4 is a front view of the computer shown in FIG. 1. FIG. 5 is a right-side view of the computer shown in FIG. 1. FIG. 6 is a rear view of the computer shown in FIG. 1. FIG. 7 is a top view of the computer shown in FIG. 1. FIG. 8 is a bottom view of the computer shown in FIG. 1. FIG. 9 is a top perspective view of the example computer of FIG. 1, showing the display in a portrait orientation. FIG. 10 is a bottom rear perspective view of the computer shown in FIG. 9.

FIG. 11 is a left-side view of the computer shown in FIG. 9. FIG. 12 is a front view of the computer shown in FIG. 9. FIG. 13 is a right-side view of the computer shown in FIG. 9.

FIG. 14 is a rear view of the computer shown in FIG. 9. FIG. 15 is a top view of the computer shown in FIG. 9; and, FIG. 16 is a bottom view of the computer shown in FIG. 9. This design relates to a computer. The computer includes a frustoconical housing to contain processing and memory components, and a display that may be rotated between landscape and portrait orientations. The broken lines immediately adjacent to the claim depict the bounds of the claimed design, while all other broken lines are directed to environment. The broken lines form no part of the claimed design.
